COMBINED LAMP AND PLANTER

Quirico Angeli, Philadelphia, Pa.

Application November 24, 1953, Serial No. 27,769

Term of patent 3½ years

(Cl. D35—3)

Fig. 1.

Fig. 2.

Fig. 3.

To all whom it may concern:

Be it known that I, Quirico Angeli, a citizen of the United States, residing at Philadelphia, Philadelphia county, Pennsylvania, have invented a new, original, and ornamental Design for a Combined Lamp and Planter, of which the following is a specification, reference being made to the accompanying drawing, forming a part hereof.

The dominant features of my design reside in the portions shown in full lines.

I claim:

The ornamental design for a combined lamp and planter, as shown and described.
